UNITED STATES PATENT OFFICE.

COLIN CAMPBELL, OF NEWARK, NEW JERSEY.

POWER-HAMMER.

1,168,850.

Specification of Letters Patent. Patented Jan. 18, 1916.

Application filed June 13, 1913. Serial No. 773,889.

To all whom it may concern:

Be it known that I, COLIN CAMPBELL, a citizen of the United States, residing at Newark, in the county of Essex and State of New Jersey, have invented certain Improvements in Power-Hammers, of which the following is a specification.

This invention relates more particularly to the valve gear or valve-operating mechanism for a hammer adapted to be automatically reciprocated by the pressure of steam, compressed air or the like, and the objects of the invention are to reduce to a minimum in such a hammer the valve-operating mechanism which is carried by the ram; to thus reduce crystallization and consequent breakage of the operating mechanisms; to provide valve operating members mounted upon the body of the hammer within the same and thus protected; to introduce into the valve-operating mechanism levers fulcrumed in the body of the hammer; to reduce the friction and wear of the operating parts; to secure simplicity of construction and operation, and to obtain other advantages and results as may be brought out in the following description.

Referring to the accompanying drawings, in which like numerals of reference indicate the same parts throughout the several views, Figure 1 is a front elevation of my improved power hammer; Fig. 2 is a central longitudinal section thereof on line A—A, Fig. 1; Fig. 3 is a sectional view on line B—B of Fig. 2; Fig. 4 is a transverse section on line C—C of Fig. 2, and Fig. 5 is a detail plan of a certain bracket for the ram.

In the specific embodiment of the invention illustrated in said drawings, the reference numeral 1 indicates the body of my improved hammer providing side walls 2, 3 and back wall 4, all preferably in one integral casting. Suitable guides 5, 5 are secured to the outside of the side walls, 2, 3, on opposite sides of the body, and a bail 6 at the top of the frame pivoted to and extending between said side walls provides means for suspending the hammer in upright position for use. On the inside of the side walls 2, 3, at the lower part thereof, are tracks 7, 8, for the slidable retention of a ram 9, and from said ram a substantially central piston rod 10 extends upwardly and is provided at its upper end with a piston

11 working within a cylinder 12 as is usual and well-known in the art. Said piston rod may be secured to the ram in any convenient way, but I prefer to provide a countersunk hole 13 transversely through the ram 60 from its front and insert a pin 14 therein, said pin passing through the piston rod, as shown in Fig. 1.

The cylinder 12 is preferably bolted to the back wall 4 of the body 1 and provided at 65 its front with a transverse slide valve 15 in a pressure chamber or steam chest 16, as is common, the cylinder having appropriate passages 17 and 18 to connect the chest with the upper and lower ends of the cylinder, 70 respectively, and a central exhaust passage 19, all of said passages opening through the valve seat 20, see Fig. 4. By sliding the valve 15 back and forth, first one passage, as 17, is placed in communication with the 75 exhaust 19 while the other one, 18, is open to the pressure chamber, and then the reverse, as will be understood by those skilled in the art. In order to slide the valve 15 on the seat 20, said valve has on its back two 80 outwardly extending ears 21, 21 spaced laterally apart in vertical planes with a nut 22 interposed between them. A valve or shift rod 23 has a threaded part midway of its 85 ends screwed into said nut 22 and projecting through suitable perforations in the ears. By this, or equivalent means, the valve may be operated upon reciprocating the shift rod 23, it being understood that said rod projects at its ends through suitable 90 packings 24, 24 in the end walls of the steam chest.

For so reciprocating the rod 23 to produce the strokes of the ram, reversing the direction of the steam or other pressure as the ram nears the end of its stroke in either direction, I provide upright levers 25, 26 fulcrumed on the opposite side-walls 2, 3 of the body 1 of the hammer, preferably in recesses 27, 27 in the said walls, as shown. The upper ends of said levers are opposite the ends of the rod 23, and preferably in outwardly open slots 28, 29, respectively, in collars 30, 31 pinned or otherwise secured to the ends of said valve rod. As shown, it is preferable to round the engaging walls 32 of the slots and levers, so as to reduce wear. Preferably, springs or other resilient means 33 are inserted between the upper ends of the levers and the adjacent side 110

walls of the body, in seats 34 sunk in the bottoms of the recesses 27, so as to keep the levers pressed in toward the valve rod and prevent rebound or knocking of the levers due to the impetus of their swing. Below the fulcrums 35 of the levers 25, 26 their inwardly facing edges provide cam surfaces 36, 37, respectively, adapted to be engaged by the ram, whereby the levers may be swung at the proper time of the stroke of the ram, to reverse its direction. That is to say, one cam surface 37 is near the top of the ram's stroke, so as to be engaged thereat, and the other is near the bottom of said stroke so as to be engaged as the ram is nearly down.

While the ram may be of any construction which will suitably engage the cam levers, I prefer to provide a ram head with some special means for facilitating this engagement, and in the drawings such means is illustrated as a bracket 38 having its ends forked to carry rollers 39, 40, said bracket being laid flatwise on the top of the ram head 91 with the two rollers in the plane of the levers 25, 26, the parts being suitably proportioned so that the rollers will engage the cam surfaces 36, 37, respectively, at the proper time and give the levers the necessary swing. For holding the bracket 38 in position I groove the two sides of the ram head rearwardly from its front, as at 41, 41 to slidably receive corresponding tongues, 42, 42 on depending portions 43, 43 of the bracket adjacent its ends, and when the bracket is slid in place a pin 44 is inserted through appropriate registering holes in the bracket and ram head, it being preferable to have the hole in the ram head intersect the large portion of the transverse countersunk hole 13 so that the end of said pin 44 may project thereinto and receive a cotter-pin or other securing means.

Obviously, as the ram approaches the lower end of its stroke the roller 39 engages the cam surface 36 of the lever 25 and swings said lever, thereby sliding the valve 15 to the other end of its stroke and reversing the relation of the passages to the pressure chamber and exhaust so as to reverse the direction of movement of the ram. When said ram approaches the other or upper end of its stroke the opposite lever 26 has its cam surface 37 engaged by the other roller 40, which slides the slide valve back again, and the direction of movement of the ram is reversed.

It will be understood that in hammers of this type the force of impact of the ram against whatever is being hammered is very great, and the blows are very rapid, and by my improved construction in mounting the cam levers 25, 26 upon the body of the hammer very little of this force of impact is transmitted to them and they are thus re-

lieved of the crystallization and breakage which would otherwise occur. It will also be noted that the ram engages the cam levers direct or without the intervention of any other levers or mechanical elements outside of itself, the means for engagement herein claimed being a part of the ram.

Obviously, various modifications and changes in the detail construction of my improved device can be made by those skilled in the art without departing from the spirit and scope of the invention, and I do not wish to be understood as restricting myself except as required by the following claims when construed in the light of the prior art.

Having thus described the invention, what I claim is:

1. In a power hammer, a body providing a slideway, a ram adapted to reciprocate in said slideway, a cylinder mounted on said body, a piston in said cylinder connected to said ram, a slide valve for said cylinder arranged transversely of the slideway, and levers arranged longitudinally of the slideway at opposite sides thereof and fulcrumed intermediate said valve and ram, said levers adapted to be engaged by the ram at one end and to engage the slide-valve at the other end.

2. In a power hammer, a body providing a slideway, a ram adapted to reciprocate in said slideway, a cylinder mounted on said body, a piston in said cylinder connected to said ram, a slide valve for said cylinder arranged transversely of the slideway, and levers arranged longitudinally of the slideway at opposite sides thereof and fulcrumed between the ram and said slide valve, said levers being adapted at their upper ends to operate said slide valve and having at their lower ends cam surfaces adapted to be engaged by the ram to swing said levers.

3. In a power hammer, a body providing a slideway, a ram adapted to reciprocate in said slideway, a cylinder mounted on said body, a piston in said cylinder connected to said ram, a slide valve for said cylinder arranged transversely of the slideway, and levers arranged longitudinally of the slideway at opposite sides thereof and fulcrumed between the ram and slide valve, said levers engaging at their upper ends the slide valve rod and adapted at their lower ends to be engaged by the ram, and springs forcing the upper ends of said levers against said slide valve rod.

4. In a power hammer, a body providing an inner slideway, a ram adapted to reciprocate on said slideway, a cylinder mounted in said body, a piston in said cylinder connected to said ram, a slide valve for said cylinder, a member movably mounted upon said body within the same and adapted to be engaged by the ram to move it in one direction, means for moving said member in the

other direction, and means for transmitting movement from said member to the slide valve.

5. In a power hammer, a body providing a slideway, a ram adapted to reciprocate in said slideway and be guided thereby, a stationary cylinder fixed in said body, a piston adapted to reciprocate in said cylinder and be guided thereby, a rod connecting said piston to said ram, a slide valve for said cylinder, and a member mounted upon said body intermediate said slide valve and ram adapted at one end to operate said slide valve and at its other end to be engaged by said ram, said ram adapted to engage said member direct by its longitudinal movement and at a certain point thereof impart movement to said member.

6. In a power hammer, a body providing a slideway, a ram adapted to reciprocate in said slideway and be guided thereby, a stationary cylinder fixed in said body, a piston adapted to reciprocate in said cylinder and be guided thereby, a rod connecting said piston to said ram, a slide valve for said cylinder, a member mounted upon said body intermediate said slide valve and ram adapted at one end to operate said slide valve and at its other end to be engaged by said ram, said ram adapted to engage said member direct by its longitudinal movement and at a certain point thereof impart movement to said member, and other means for returning said member to initial position.

35 7. In a power hammer, a body providing a slideway, a ram adapted to reciprocate in said slideway and be guided thereby, a stationary cylinder fixed in said body, a piston adapted to reciprocate in said cylinder and be guided thereby, a rod connecting said piston to said ram, a slide valve for said cylinder, a member mounted upon said body intermediate said slide valve and ram adapted at one end to operate said slide valve and at its other end to be engaged by said ram, said ram adapted to engage said member direct by its longitudinal movement and at a certain point thereof impart movement to said member, and means for engaging the slide valve end of said member to return it to initial position.

8. In a power hammer, a body providing a slideway, a ram head adapted to reciprocate in said slideway and be guided thereby, a stationary cylinder fixed in said body, a piston adapted to reciprocate in said cylinder and be guided thereby, a rod connecting said piston to said ram head, a slide valve for said cylinder, a lever fulcrumed upon said body intermediate said slide valve and ram head adapted at one end to operate said slide valve and having a cam surface on its other arm, and means on said ram head adapted to move longitudinally therewith in alinement with said lever and engage said

cam surface to swing the lever and operate the slide valve.

9. In a power hammer, a body providing a slideway, a ram head adapted to reciprocate in said slideway and be guided thereby, a stationary cylinder fixed in said body, a piston adapted to reciprocate in said cylinder and be guided thereby, a rod connecting said piston to said ram head, a slide valve for said cylinder, a lever fulcrumed upon said body intermediate said slide valve and ram head adapted at one end to operate said slide valve and having a cam surface on its other arm, means on said ram head adapted to move longitudinally therewith in alinement with said lever and engage said cam surface to swing the lever and operate the slide valve, and means for engaging the slide valve end of said lever to return it to its initial position.

10. In a power hammer, a body providing a slideway, a ram head adapted to reciprocate in said slideway and be guided thereby, a stationary cylinder fixed in said body, a piston adapted to reciprocate in said cylinder and be guided thereby, a rod connecting said piston to said ram head, a slide valve for said cylinder, a lever fulcrumed upon said body intermediate said slide valve and ram head adapted at one end to operate said slide valve and having a cam surface on its other arm, means on said ram head adapted to move longitudinally therewith in alinement with said lever and engage said cam surface to swing the lever and operate the slide valve, and a spring for engaging the slide valve end of said lever to return it to its initial position.

11. In a power hammer, a body providing a slideway, a ram head adapted to reciprocate in said slideway and be guided thereby, a stationary cylinder fixed in said body, a piston adapted to reciprocate in said cylinder and be guided thereby, a rod connecting said piston to said ram head, a slide valve for said cylinder, a lever fulcrumed upon said body intermediate said slide valve and ram head adapted at one end to operate said slide valve and having a cam surface on its other arm, means on said ram head adapted to move longitudinally therewith in alinement with said lever and engage said cam surface to swing the lever and operate the slide valve, and a spring at the opposite side of the slide valve end of said lever from said slide valve holding the lever thereagainst.

12. In a power hammer, a body providing a slideway, a ram head adapted to reciprocate in said slideway and be guided thereby, a stationary cylinder fixed in said body, a piston adapted to reciprocate in said cylinder and be guided thereby, a rod connecting said piston to said ram head, a slide valve for said cylinder, levers fulcrumed upon said body intermediate said slide valve and

ram head adapted at one end to engage said slide valve and having cam surfaces on their other arms, and means on said ram head adapted to move longitudinally therewith in alinement with said levers and engage said cam surfaces alternately on up and down strokes to swing said levers and operate the slide valve.

13. In a power hammer, a body providing a slideway, a ram head adapted to reciprocate in said slideway and be guided thereby, a stationary cylinder fixed in said body, a piston adapted to reciprocate in said cylinder and be guided thereby, a rod connecting said piston to said ram head, a slide valve for said cylinder, levers fulcrumed upon said body intermediate said slide valve and ram head adapted at one end to engage said slide valve and having at their other ends cam surfaces one higher than the other, and means on said ram head adapted to move longitudinally therewith in alinement with said levers and engage one cam surface on upstroke of the ram and the other cam surface on downstroke of the ram so as to swing said levers alternately in opposite directions and operate the slide valve.

14. In a power hammer, a body providing a slideway, a ram head adapted to reciprocate in said slideway and be guided thereby, a stationary cylinder fixed in said body, a piston adapted to reciprocate in said cylinder and be guided thereby, a rod connecting

said piston to said ram head, a slide valve for said cylinder, levers fulcrumed upon said body intermediate said slide valve and ram head adapted at one end to engage said slide valve and having at their other ends cam surfaces one higher than the other, and means at separate circumferential points of said ram head in substantially the same transverse plane thereof adapted to move longitudinally therewith in alinement with said levers and engage one cam surface on upstroke of the ram and the other cam surface on downstroke of the ram so as to swing said levers alternately in opposite directions and operate the slide valve.

15. In a power hammer, a body providing a slideway and a longitudinal slot, a ram adapted to reciprocate in said slideway and be guided thereby, a stationary cylinder fixed in said body, a piston adapted to reciprocate in said cylinder and be guided thereby, a rod connecting said piston to said ram, a slide valve for said cylinder and a member mounted upon said body in said slot intermediate said slide valve and ram adapted at one end to operate said slide valve and at its other end to be engaged by said ram at a certain point of movement of the latter and actuated thereby.

COLIN CAMPBELL.
